UNITED STATES PATENT OFFICE.

CHARLES JAQUET, OF STRASBOURG-KOENIGSHOFFEN, FRANCE.

PLANE SIEVE.

Application filed August 29, 1921. Serial No. 496,513.

To all whom it may concern:

Be it known that I, CHARLES JAQUET, a citizen of France, residing at Strasbourg-Koenigshoffen, Alsace, France, have invented new and useful Improvements in Plane Sieves, (for which I have obtained a patent in Germany, No. 328,719 of July 26, 1916 and have filed applications in France, December 11, 1920, No. 156; Belgium, March 10, 23, 1921, No. 235,863, and Switzerland, March 29, 1921 No. 11,809), of which the following is a specification.

This invention relates to improvements in plane sieves, the object being to provide an improved device of this character, by means of which material may be more effectively sifted. The invention consists in the construction and arrangement of devices hereinafter described and claimed.

20 In the drawings:—

Fig. 1 is a plan of a sieve constructed in accordance with this invention.

Fig. 2 is a longitudinal section on the line A A of Figure 1 and Figure 3 is a cross section on the line C D of Fig. 1.

In the embodiment of my invention the sieve as shown in Figure 1 is divided along its length into a number of divisions 1, 2 and 3, each division being either circular, hexagonal, octagonal or polygonal and of which the inlets and outlets 4 and 5 are narrower than the sieve surfaces. The sieve divisions are made much wider than said inlets and outlets so that the material in sequence of the circular movement of the

sieve can spread out and thus completely cover and utilize the sifting surface.

The material to be sifted cannot be thrown in a zig zag path from one side to the other as the two walls 7 and 8 are some distance apart. In this manner a circular movement is imparted to the material to be sifted which results in an intensive sifting action. The sifting surfaces are thus completely and entirely utilized so that the efficiency is considerably increased.

According to the composition of the material to be sifted one side of the sifting surface may be provided with transporting plates 9 so as to impart a greater or less speed to the material to be sifted.

Having now particularly described and ascertained the nature of our said invention and in what manner the same is to be performed, we declare that what we claim is:—

In a plane sorting device a sieve surface having cross traverses, whereby above each transverse on both sides of the longitudinal walls of the sieve surface wedge shaped corners are disposed, which consist of frames whereby the individual cross compartments receive a round or approximately round sieve surface, said corner serving at the same time as inlet and outlet passages between the individual compartments and transporting plates arranged at one side of the cross compartments and extending partly thereacross.

In witness whereof I affix my signature.
CHARLES JAQUET.
